UNITED STATES PATENT OFFICE.

PHILIP BOSCHE, OF CORTLAND, NEW YORK.

GAME.

SPECIFICATION forming part of Letters Patent No. 431,762, dated July 8, 1890.

Application filed December 17, 1889. Serial No. 334,012. (No model.)

To all whom it may concern.:

Be it known that I, PHILIP BOSCHE, of Cortland, in the county of Cortland and State of New York, have invented an Improvement 5 in Games, of which the following is a full, clear, and exact description.

My invention relates to a game, and has for its object to provide a toy base-ball field, by the manipulation of which a ball, block, 10 or cube representing a player may be made to travel, in accordance with certain rules, around the field; and the invention consists in the novel construction and combination of the several parts, as will be hereinafter fully 15 set forth, and pointed out in the claims.

Reference is to be had to the accompanying drawings, forming a part of this specification, in which similar figures of reference indicate corresponding parts in both the views.

20 Figure 1 is a plan view of the game-board, and Fig. 2 is a transverse section on line *x* *x* of Fig. 1.

In carrying out the invention I prefer to construct the board substantially in the shape 25 of a box, as shown in the drawings, which box is made up of a base or bottom 10, sides 11 and ends 12, and the said box is also preferably covered at its top by a pane of glass 13 or other transparent material. The bottom 30 of the box represents the field, and upon the said field a diamond 14 is arranged ordinarily in the following manner: The sides of the diamond are formed by producing ribs 15 upon the field, which ribs may form an integral portion of the bottom or be attached thereto. The ribs at each side are two in 35 number, and are placed parallel, so as to form a depressed space or runway 16 between them. These ribs extend to within a short distance 40 of each corner of the diamond, where they unite with a solid embossed surface 17. The embossed surfaces 17 represent the bases, and the depressed spaces 16 the path between the bases.

45 In the home-plate 18, which is formed in similar manner as the bases, but slightly larger, a depression or cavity 19 is produced, and within the diamond, extending from the home-plate, two parallel ribs 20 are formed 50 upon the bottom 10 of the board, the space between which ribs represents the pitcher's

box; and for a purpose hereinafter described an embossed hollow square 21 may also be formed upon the bottom of the box within the diamond, one side of which square forms 55 the lower boundary of the pitcher's box above referred to.

In connection with the board I employ ordinarily a globule of mercury 23, or a small ball, cube, or similar article, and sometimes 60 a globule of mercury and a single ball 24 are employed in playing the game, as illustrated in the drawings.

I desire it to be understood that I do not confine myself to the arrangement of the diamond upon the bottom of the box, as the diamond may be substituted by a race-track, or the field may be laid out in such manner that any other game than base-ball may be played.

In operation, when the globule of mercury 70 or a single ball is employed, the game is started by placing the globule of quicksilver or the ball or marble in the center of the pitcher's box. The board is now tilted by the operator in such manner as to work the globule or 75 ball into the cavity 19 at the home-plate, and then around the diamond over the embossed bases, and again stopping in the said cavity 19. If successfully accomplished without allowing the quicksilver or marble to leave the spaces 80 or paths 16, or the bases themselves, the game is ended. In the event of a failure to make the complete circle of the diamond, the operator must start again in the center of the pitcher's box. A regular game of base-ball 85 can be played by two parties representing the nines by calling every successful attempt to lodge the quick silver in the home-plate cavity a hit, and every unsuccessful attempt a strike, three strikes an out, and so on, following the rules of base-ball as nearly as possible, after a hit is made, proceeding as in the outstart of the game.

If the path from the home-plate is safely traveled to the first base, and said base is 95 passed and the globule or ball should leave the track before the second base is reached, the hit is intended to be a safe one, and the player is entitled to hold first base; and if the path between the home-plate and second 100 base is safely traveled, and the first and second bases safely crossed, and the ball or glob-

ule should leave the track between the second and third bases, but fail to cross the third base, the player is entitled to keep the second base, and so on. The record of the bases may 5 be kept by inserting pins in apertures produced in the top of the box at its corners, or in any other suitable or approved manner.

When the globule of mercury and a single ball or marble are used in playing the game, 10 the marble is placed in the square 21 at the end of the pitcher's box and the globule of mercury in the pitcher's box; and in order to make any successful play, the mercury globule being operated as heretofore described, 15 the ball or marble must not leave the square 21.

Having thus described my invention, I claim as new and desire to secure by Letters Patent—

20 1. In a game, the combination of a box-like structure having a diamond produced on its bottom, the diamond being formed of parallel and spaced ribs 15, forming runways 16 be-

tween them, and solid embossed corner-surfaces 17 18, the corner 18, having a depression 19 produced therein, and parallel and spaced ribs 20, extending inward therefrom, the space between the ribs forming the pitcher's box, and a globule of mercury adapted to travel in the space between the ribs and 30 over the embossed corner-surfaces, substantially as described.

2. The herein-described game-board, consisting of a box-like structure having a glass cover and provided on its bottom with the 35 diamond 14, formed of the spaced ribs 15 and corner embossed surfaces 17 and 18, the corner 18, having a depression 19, the spaced ribs 20, leading inward from the corner 18, and the hollow square 21 at the end of the 40 ribs 20, substantially as herein shown and described.

PHILIP BOSCHE.
